EX

OR D 13,283

DESIGN FOR A WINDOW-SHADE.

Design No. 13,283, dated September 5, 1882.

UNITED STATES PATENT OFFICE.

CAMILLE REINHARDT, OF NEW YORK, N. Y., ASSIGNOR TO WARREN,
FULLER & CO., OF SAME PLACE.

DESIGN FOR A WINDOW-SHADE.

SPECIFICATION forming part of Design No. 13,283, dated September 5, 1882.

Application filed August 7, 1882. Term of patent 3½ years.

To all whom it may concern:

Be it known that I, CAMILLE REINHARDT, a citizen of the United States, residing at the city of New York, in the county of New York and State of New York, have invented or designed a new and useful ornamental Design for Window Shades or Curtains, of which the following is a full and clear description, and which will be readily understood by reference to the accompanying drawing, illustrating the same.

The design consists of a richly-ornamented transverse band across the body of the curtain, the ornamentation being in the form of foliation. Three straight and distinct transverse lines, A, A', and A², divide the field of ornamentation into two sections, B and B'. The lower one of these, B, is quite narrow as compared with the other one, being only about one-tenth or one-twelfth (more or less) of the width of the upper and larger field or section, B'. This lower field or section, B, is ornamented with small sloping figures of branches or leaves C, C', and C², which are placed at about equal distances from each other. The figures C are "lanceolate" branches, the figures C' are "obcordate," and the figures C² are "palmate." These various figures are arranged to pleasingly alternate each other, and the bottom ends or stems of them touch the bottom band, A, from which they slope upward and diagonally at an angle of about forty-five degrees, and extend toward the middle line, A', until their top ends nearly touch it. The upper field or section of ornament B' is richly filled with foliated figures, the most prominent of which are the figures D, showing a large branch with "pinnately-compound" leaves, and the fern-like figures

E, showing "bipinnate" leaves. The next prominent figures in the section B' are the figures F of "ob lanceolate" leaves. One of these leaves, or branches of them, forms a central figure in the section B', and one of them terminates the field at either end. The subdivisions of the sections B' between the central ornament, F, and the end figures of the same description each have one of the ornaments D and one of those marked E. Interwoven with the branches of the figures D, E, and F, above described, are branchlets and leaves G of obcordate formation, H of lanceolate formation, I of palmate formation, and J of "palmately-three-cleft" formation, the whole intertwined and interfoliated, so as to fill and enrich the section B'. The spaces left between the stems of the branches of the above-described leaflets where they join to or start from the base-line A' of the section are filled with grass tufts K, so as to complete the ornamentation and filling of the lower portion of the section B'.

Having described my invention, I claim—

The design for a window-curtain or other similar work, consisting of the two transverse fields of ornamentation B and B', formed by the heavy transverse lines A, A', and A², the lower section, B, being ornamented with the leaflets C, C', and C², and the upper section or field of ornament, B', with the principal figures D, E, and F, and with the sub-figures G, H, I, J, and K, substantially as described.

CAMILLE REINHARDT.
